WATCH BAND DISPLAY STAND

Ernest H. Augat, Attleboro, Mass.

Application June 3, 1950, Serial No. 10,329

Term of patent 3½ years

(Cl. D80—9)

To all whom it may concern:

Be it known that I, Ernest H. Augat, a citizen of the United States, residing at Attleboro, in the county of Bristol and State of Massachusetts, have invented a new, original, and ornamental Design for a Watch Band Display Stand, of which the following is a specification, reference being had to the accompanying drawing, constituting a part hereof.

Fig. 1 is a front perspective view from above taken from in front of and above the base with the holder arm in raised position.

Fig. 2 is an oblique perspective view thereof, with the holder arm in raised position.

Fig. 3 is top plan view with the holder arm in lowered position.

The dotted showing in Fig. 1 is only for illustrative purposes.

I claim:

The ornamental design for a watch band display stand, substantially as shown and described.

ERNEST H. AUGAT.
